United States Patent Office.

GEORGE W. HUNTER, OF VERSAILLES, INDIANA.

Letters Patent No. 96,435, dated November 2, 1869.

IMPROVEMENT IN FENCE.

The Schedule referred to in these Letters Patent and making part of the same.

To all whom it may concern:

Be it known that I, GEORGE W. HUNTER, of Versailles, in the county of Ripley, and State of Indiana, have invented a new and useful Improvement in Fences; and I do hereby declare the following to be a full and correct description of the same, sufficient to enable others skilled in the class to which my invention appertains, to fully understand and construct the same, reference being had to the accompanying drawings, which make part of this specification, and which represent a perspective view of a fence constructed according to my invention.

The nature of my invention consists in the arrangement of short and long rails, to construct a fence running over a hill or rise in the ground, so that the panels of the same shall all be level and of a height.

A, in the drawings, may represent the rails of a common worm-fence, on even ground, which fence is to be run over a hill, B.

C represents a series of short rails, laid with one end between rails A and the other on the ground.

These rails C increase in length till they do not rest any more on the ground, but between the ends of longer rails, D, the other ends of which rest on the

ground until one is level with the top of the hill, when they are laid between the ends of shorter rails, E, and, in the reverse manner, down the other side of the hill.

To make the panels of a height, I lay the ends of the three uppermost rails D', of the panel D, nearest to the base of the hill, upon each other, instead of between the rails C, while their other ends rest between the ends of rails E.

Rails F, placed vertically against the corners where the rails interlock, brace the fence.

In this manner a worm-fence, the panels of which are of a height, is constructed level over a hill or any rise in the ground.

Having thus described my invention,

What I claim as new, and desire to secure by Letters Patent, is—

The arrangement, in a worm-fence, of the rails C, D, D', E, and F, in the manner shown, and for the purpose described.

GEO. W. HUNTER.
